GAS TUBE INPUT CIRCUIT

Jerome Kurshan, Princeton, N. J., assignor to
Radio Corporation of America, a corporation
of Delaware

Application March 30, 1951, Serial No. 218,299

12 Claims. (Cl. 315—349)

1

This invention relates to improvements in gaseous electron tube circuits, and particularly to an improved circuit for operating a gas filled electron tube of the type wherein the functions of ionizing the tube gas and of passing current through the ionized gas are separated.

In a copending application of E. O. Johnson, Serial No. 185,745, filed September 20, 1950, and assigned to the assignee of the present invention, there is described a gas filled electron tube in which space charge neutralizing ions are generated by an auxiliary ionizing discharge of electrons between an auxiliary emitter and one or more of the main tube electrodes. With this arrangement, two very important advantages are attained.

First, it is found that very high current can be passed between the main emitter and collector electrodes at potentials far below those required to ionize the gas. Second, it is found that the current flow between main emitter and collector can be controlled in various ways, one of which is by means of a control electrode similar to that used in the conventional vacuum tube.

For simplicity, gas tubes of the type just described are referred to herein as "separated function" gas tubes.

While the separated function gas tube has been found very useful for many applications, it has one characteristic that causes difficulty in some cases. It has been found that the grid-voltage plate-current characteristic is not entirely linear. Consequently, high fidelity reproduction of input signals is not always attainable with the circuits heretofore proposed for operating separated function gas tubes.

It is, therefore, one object of the present invention to provide an improved circuit for operating a separated function gas tube so as to permit the use of such tubes as high fidelity signal amplifiers.

A further object of the invention is to provide a separated function gas tube energizing circuit which will overcome nonlinearity in the grid-voltage plate-current characteristics of such tubes.

In accordance with the invention, the foregoing and other related objects and advantages are attained in a circuit wherein advantage is taken of the nonlinear grid-voltage grid-current characteristic of the separated function gas tube. During operation, ion current will flow to a negatively biased control grid in a separated function gas tube. It has been found that the curve relating this ion current to the grid voltage (herein

referred to as the grid-voltage grid-current characteristic) is nonlinear. Furthermore, the nonlinearity of the grid-voltage grid-current characteristic can be relied on to compensate in large measure for the nonlinearity in the grid-voltage plate-current characteristic.

By providing a relatively high impedance in the grid input circuit, the grid voltage can be made to follow the applied signal voltage in a nonlinear manner so as to attain the desired linear relation between signal input and signal output. In accordance with a further feature of the invention, if the linearizing grid circuit impedance also is made nonlinear, still further linearization of overall circuit operation can be attained.

A more complete understanding of the invention can be had by reference to the following description of illustrative embodiments thereof, when considered in connection with the accompanying drawing, wherein

Fig. 1 is a view in cross-section of a typical tube such as may be used in accordance with the present invention;

Fig. 2 shows a typical grid-voltage plate-current characteristic curve for a tube of the type shown in Fig. 1;

Fig. 3 shows a typical grid-voltage grid-current characteristic curve for a tube such as is shown in Fig. 1;

Fig. 4 is a schematic diagram showing in general form a separated function gas tube circuit arranged in accordance with the invention;

Fig. 5 is a circuit diagram showing one specific embodiment of the present invention;

Fig. 6 shows the relation between signal input and signal output voltage attainable with a circuit such as is shown in Fig. 5;

Fig. 7 is a circuit diagram of a second specific embodiment of the present invention;

Fig. 8 shows the current-voltage curve of a nonlinear impedance element;

Figs. 9, 10 and 11 are circuit diagrams showing further embodiments of the invention.

Referring to Fig. 1 of the drawing, there is shown in cross-section a separated function gas tube of the type more fully described and claimed in the above-mentioned copending application of Johnson. In Fig. 1, a gas tight envelope 10 is provided with a cathode 12. A U-shaped control electrode or grid 14 and a U-shaped anode 16 partially surround the cathode 12. The grid 14 comprises a plurality of parallel wires 15 which are supported in spaced relation. The anode 16 may be a sheet metal element.

Opposite the open ends of the grid 14 and the anode 16 there is mounted a cylindrical focusing electrode 18 provided with an elongated slot 20 facing the open ends of the grid and anode structures. An auxiliary cathode 22 is mounted coaxially within the focusing electrode 18.

A tube having a structure such as that shown in Fig. 1 can be operated as follows:

If a voltage greater than the ionizing voltage of the gas in the tube is applied between the auxiliary cathode 22 and main cathode 12, an electron current will flow which will ionize the gas in the tube. As a result, a highly conductive mixture or "plasma" of ions and electrons will be created within the tube envelope. The focusing electrode 18 is effective to concentrate the ionizing current, making it possible to obtain high plasma densities with very small amounts of current or power. With the tube gas ionized to create plasma in the manner just described, it becomes possible to pass a relatively high current between the main cathode and the main anode with a voltage drop which may be of the order of 0.1 volt or less. Furthermore, it becomes possible to control this main cathode-anode current by means of the control electrode 14 disposed in the space path as shown.

As was previously stated, one of the difficulties encountered with the tube shown in Fig. 1 arises from nonlinearity of the grid-voltage plate-current characteristic. This is illustrated by the curve shown in Fig. 2, which may be regarded as generally typical of such tubes. From Fig. 2, it can be seen that an incremental grid voltage change in the vicinity of the "-15" volt point on the chart will produce a much smaller change of plate current than would an equal change in the vicinity of, say, the "-5 volt" point. For some applications, this is of little consequence, and would even be advantageous in a control system, for example, where a nonlinear response is required approximating that of the curve shown.

However, where faithful reproduction of the input signal is required, nonlinearity is objectionable.

In accordance with the present invention the nonlinearity of the grid-voltage plate-current characteristic is overcome by taking advantage of the somewhat similar nonlinearity of the grid-voltage grid-current characteristic.

As is shown in Fig. 3, for example, when the control grid of a separated function gas tube is made negative with respect to the main cathode thereof, current will flow to the control grid. It should be noted that this current is not an electron current, but rather arises from the flow of positive ions to the control grid. As is shown by the curve of Fig. 3, the relation between grid-current and grid voltage is quite nonlinear, with the degree of nonlinearity increasing somewhat as the grid-voltage approaches zero from the negative direction. A comparison of Figs. 2 and 3 will show that both curves have more nonlinearity in the region between -10 and zero than in the region between -25 and -10. Thus, the curvature of the two curves is sufficiently similar to permit combination thereof in suitable circuits to provide a linearizing action in the operation of a separated function gas tube.

For example, there is shown in Fig. 4 the circuit diagram of a separated function gas tube system embodying the general principles of the present invention. The circuit of Fig. 4 comprises a gas tube 10 having electrodes 12-22 previously identified in connection with the dis-

cussion of Fig. 1. Between the anode 16 and the main cathode 12, there is connected a load circuit 24 in series with an operating voltage source, shown as a battery 26. Between the main cathode 12 and the auxiliary cathode 22 there is connected a source of ionizing voltage, shown as a battery 28, in series with a current limiting resistor 30. The shield electrode 18 is connected to the auxiliary electrode 22.

As thus far described, the circuit shown in Fig. 4 is, in general, similar to circuits such as conventionally are used with a separated function gas tube. In the usual case, a control voltage applied between the control grid 14 and the main cathode 12 would determine the current flow between the main cathode 12 and anode 16 and, hence, through the load circuit 24.

In accordance with the present invention, the current flowing through the load circuit 24 is to be substantially linearly related to the signal voltage obtained from a signal source 32. The signal source 32 may take any one of a number of different forms, specific examples of which are given hereinafter. The signal source 32 is adapted to be connected through a pair of input terminals 35 in series with a bias voltage source, shown as a battery 34, and a high impedance element 36, between the control grid 14 and the main cathode 12.

In operation, the voltage source 34 will establish an operating point for the tube on the curve shown in Fig. 3. The alternating output voltage of the signal source 32 will vary the tube operating point about the fixed point established by the battery 34. In effect, then, there will be applied a variable amplitude voltage across a series circuit consisting of the high impedance 36 and the grid-main cathode space in the tube 10. This variable voltage will cause a variable current to flow to the grid 14 and back through the impedance 36, the source 32 and the battery 34. This current will be substantially linearly related to the voltage variations arising from the signal source 32. However, it is evident from consideration of the curved characteristic shown in Fig. 3 that the grid-voltage will not be linearly related to the output of the signal source. Rather, it will have a nonlinear relation corresponding to the curve of Fig. 3. Accordingly, the load circuit current will be much more linearly related to the signal voltage than would be the case if the high impedance 36 were eliminated from the circuit.

In Fig. 5, a circuit illustrating the foregoing principle is shown in more specific form. In the circuit of Fig. 5, a separated function gas tube 10 is connected as an amplifying element between a signal source, comprising a phonograph pickup 32a, and a load shown as a loudspeaker 24a. The voice coil 25 of the loudspeaker 24a is connected between the operating voltage source 26 and the gas tube anode 16. The input circuit for applying the signal from the phonograph pickup 32a to the loudspeaker output tube 10 comprises a triode vacuum tube 36a. The triode anode 40 is connected directly to the gas tube control grid 14. The triode cathode 40 is connected through a bias network 42 and a voltage source 34 to the gas tube main cathode 12. The triode control grid 44 is connected through a coupling capacitor 46 and one of the input terminals 35 to the pickup 32a. A grid leak resistor 48 completes the triode tube circuit.

In the circuit of Fig. 5, it can be seen that the triode 36a effectively comprises a variable high impedance in series with the voltage source 34.

between the gas tube control grid 14 and main cathode 12. The voltage source 34 provides both bias voltage for the gas tube 10 and operating voltage for the triode 36a. Assuming that the triode 36a is operated on the linear portion of its characteristic, then the voltage at the gas tube control grid 14 will be nonlinearly related to the pickup output signal, in accordance with the curve shown in Fig. 3 and as already described generally in connection with Fig. 4.

At first glance, it might seem that the circuit of Fig. 5 is not essentially different from similar separated function gas tube circuits such as are shown, for example, in the copending application of E. O. Johnson, Serial No. 203,948, filed January 2, 1951, and assigned to the assignee of the present invention. However, in the circuits shown in the last-mentioned Johnson application, wherein a vacuum tube comprises part of the input circuit of a separated function gas tube, the grid-cathode space of the gas tube is in shunt with the vacuum tube, rather than in series with the triode and its operating voltage source 34 as in the circuit of Fig. 5. The shunt arrangement involves the following difficulties where linearity of the gas tube output is important:

In order for the vacuum tube to have a linearizing effect, it is essential to have a relatively large load impedance connected between the vacuum tube anode and the operating voltage source. Otherwise, the vacuum tube will not present the required high impedance in the grid-main cathode circuit of the gas tube. On the other hand, if a large anode load impedance is used, then it becomes difficult to operate the vacuum tube at all, and a much larger operating voltage source is required. In the circuit of Fig. 5, by comparison, the operating voltage source for the vacuum tube 36a is in series with the grid-main cathode space of the gas tube and therefore does not involve the anode load impedance problem just mentioned.

In Fig. 6 there is shown a curve relating the triode grid-cathode voltage to load current for a circuit of the type shown in Fig. 5. It can be seen that such a circuit provides a linear input-output relation for load currents between approximately 80 and 160 ma.

By using a multigrid tube in the gas tube input circuit, the relations shown in Fig. 6 can be caused to shift so that linear operation is obtained at different values of gas tube load current. This occurs because operation is extended into the nonlinear region of the vacuum tube whose characteristic is determined by the auxiliary grid voltage. In other words, by suitably adjusting the voltage on auxiliary grids in the vacuum tube, the region of linear operation of the gas tube can be shifted. A circuit illustrating this arrangement is shown in Fig. 7, wherein a pentode vacuum tube 36b has been substituted for the triode 36a of Fig. 5. The pentode suppressor grid 50 is internally connected to the cathode 52. The screen grid 54 is supplied with a variable voltage from a source 56. In other respects, the circuit of Fig. 7 corresponds to that shown in Fig. 5. By varying the screen grid voltage 56, the region for linear operation of the gas tube 10 can be shifted so as to extend, say, from 40 ma. to 120; from 50 to 130, etc.

In order to increase the extent of the linear operation region on the curve of Fig. 6, it becomes necessary to use a suitable nonlinear impedance element in the gas tube input circuit.

The current-voltage curve that the nonlinear

impedance element should have for any given case can be determined by assuming specific values of input voltage, V_i , and gas tube anode current I_a , to obtain an expression relating these two parameters. Input voltage V_i is here taken to mean the total voltage in the grid-cathode circuit of the gas tube; in Fig. 4, for example, the instantaneous sum of the voltages of the battery 34 and the signal source 32. From the curves of Figs. 2 and 3, one then can obtain a table of the values of current-voltage relationship required for the unknown.

For example, it would be reasonable to have a situation in which anode current I_a is to vary from 200 ma. at zero input voltage V_i to 20 ma. for 40 input volts. This could be expressed as:

$$(1) \quad I_a = 200 - 4.5 V_i$$

The voltage V_x across the impedance 36 would be related to the input voltage V_i and the gas tube grid-to-cathode voltage V_g by the expression:

$$(2) \quad V_x = V_i - V_g$$

From equations (1) and (2), and the curves of Figs. 2 and 3, the following table can be developed:

Table I

I_a ma.	V_i volts	V_g volts	I_g ma.	V_x volts
48	34.0	11.2	1.66	22.8
69	29.3	7.7	1.40	21.6
92	24.0	5.0	1.16	19.0
112	19.6	3.5	.93	16.1
130	15.5	2.6	.74	12.9
147	11.8	1.9	.58	9.9
163	8.2	1.4	.43	6.8
177	5.1	1.2	.32	3.9

From Table I, the values of V_x and I_g can be used to plot the current-voltage curve that a nonlinear impedance element must have to satisfy the linearity requirements of the system. Such a curve is plotted in Fig. 8.

One nonlinear element that will provide a characteristic very similar to that shown in Fig. 8 is an inversely operated germanium crystal rectifier. That is, if voltage is applied across a rectifier of this type in a direction such as to cause current to flow inversely through the rectifier, the current-voltage relation will be substantially as shown in Fig. 8.

A gas tube input circuit utilizing a germanium crystal rectifier is shown in Fig. 9, wherein the input circuit for a separated function gas tube 10 comprises the series combination of a germanium crystal rectifier 36c, a signal source 32, and a bias voltage source 34. Due to the nonlinear impedance presented by the rectifier 36c to the flow of grid current therethrough, a much more effective linearization of the gas tube output current can be obtained.

Other nonlinear impedance elements similarly can be used in the gas tube input circuit to improve linearization. For example, as is shown in Fig. 10, a "thyrite" element 36d can be connected in series relation with a signal source 32 and bias voltage source 34 between the gas tube control grid 14 and main cathode 12. As is well known, a thyrite element comprises a silicon-carbide ceramic material having nonlinear resistance characteristics, such that with increasing voltage the resistance falls considerably.

A further type of nonlinear impedance element suitable for use in circuits of the type contemplated by the present invention comprises a semiconductor element or so-called transistor. In Fig.

11; a transistor 36d is shown connected in the signal input circuit of a separated function gas tube 10 to obtain linearizing action. The transistor collector 60 is connected to the gas tube control grid 14. The transistor base 62 is connected through a signal source 32 and operating voltage source 34 to the gas tube main cathode 12. The transistor emitter 64 is connected through a current limiting resistor 66 and bias voltage source 68 to the base 62. With this arrangement, the collector-to-base circuit of the transistor 36e will comprise a nonlinear variable impedance in the grid-main cathode circuit of the gas tube 10. Variation of the emitter bias provided by the source 68 can be utilized to alter or shape the circuit characteristic.

From the foregoing, it can be seen that the present invention provides a variety of simple and efficient arrangements for obtaining a linear relation between signal source voltage and output current in a separated function gas tube circuit.

What is claimed is:

1. In a circuit for controlling in accordance with a signal voltage the main cathode-anode current of a gas filled electron tube of the type having an anode, a main cathode, a control grid therebetween, and an auxiliary cathode, the combination of a high impedance element connected to said control grid, and means to pass through said impedance element and through the grid-main cathode space in said tube a current of instantaneous amplitude determined by the instantaneous amplitude of said signal voltage.
2. A circuit as defined in claim 1 wherein said high impedance element comprises a thyrite resistor.
3. A circuit as defined in claim 1 wherein said high impedance element comprises a germanium crystal rectifier.
4. A circuit as defined in claim 1 wherein said high impedance element comprises a vacuum tube having an anode electrode connected to said gas tube control grid and having a control electrode connected to receive said signal voltage.

5. A circuit as defined in claim 1 wherein said high impedance element comprises a semiconductor element, said semiconductor element having a first electrode connected to said gas tube control grid and having a second electrode connected to said gas tube cathode, and means to apply said signal voltage in series with said second electrode and said gas tube cathode.

6. In a circuit for operating a gas filled electron tube of the type having an anode, a cathode, a control electrode therebetween, and an auxiliary electrode cooperable with one of said electrodes for passing ionizing current through the tube gas, the combination of a signal voltage source, a unidirectional voltage source, a high impedance element, and a circuit connecting said voltage sources and said impedance element in series between said main cathode and said control electrode.

7. In a circuit for operating a gas filled electron tube of the type having an anode, a cathode, a control electrode therebetween, and an auxiliary electrode cooperable with one of said electrodes for passing ionizing current through the tube gas, the combination of a high impedance element connected to said control electrode, and means to apply across the series combination of said impedance and the space path between said control electrode and said cathode a signal voltage for controlling the cathode-anode current through said gas tube.

8. In a circuit for operating a gas filled electron tube of the type having an anode, a cathode, a control electrode therebetween, and an auxiliary electrode cooperable with one of said electrodes for passing ionizing current through the tube gas, the combination of a variable impedance element connected to said control electrode, a voltage source connecting said impedance in series with the space path between said control electrode and said cathode, and means to vary the impedance of said variable impedance element in accordance with a signal voltage to be amplified.

9. A circuit as defined in claim 8 wherein said variable impedance element comprises a vacuum tube having an anode connected to said control electrode and having a cathode connected to said gas tube cathode.

10. A circuit as defined in claim 8 wherein said variable impedance element comprises a semiconductor element.

11. In a circuit for operating a gas filled electron tube of the type having a plurality of electrodes including a first pair of electrodes cooperable to pass ionizing current through the gas in said tube, a second pair of electrodes for passing current through the ionized gas, and a control electrode between said last named electrode pair for controlling said last named current, the combination of a source of voltage, an impedance element, a circuit connecting said source and said impedance in series between said control electrode and one of said last named pair of electrodes, and means to vary the current flowing through said last named circuit in accordance with a signal voltage to be amplified.

12. A gas tube circuit comprising a gas filled electron tube having a main cathode electrode, an anode electrode, an electrode for controlling current flow between said main cathode and anode, and an auxiliary cathode from which ionizing current can be drawn to one of said electrodes, a first voltage source, means connecting said main cathode and said auxiliary cathode across said voltage source, a second voltage source, a variable impedance, and a circuit connecting said second voltage source and said variable impedance in series between said control electrode and said main cathode.
